FREDERICK W. COLE, OF NEWTON, MASSACHUSETTS, ASSIGNOR TO GAMEWELL FIRE ALARM TELEGRAPH CO., OF NEW YORK, N. Y., A CORPORATION OF NEW YORK.

SIGNAL-BOX WITH LOCAL-ALARM MECHANISM.

1,265,749.

Specification of Letters Patent.

Patented May 14, 1918.

Application filed May 10, 1915. Serial No. 26,934.

To all whom it may concern:

Be it known that I, FREDERICK W. COLE, a citizen of the United States, residing at Newton, in the county of Middlesex and State of Massachusetts, have invented an Improvement in Signal-Boxes with Local-Alarm Mechanism, of which the following is a specification.

This invention relates to signal-boxes equipped with a local-alarm. Some boxes are provided with a normally wound signaling-mechanism, which, when released, will operate to send its signal, and others are equipped with a normally unwound signaling-mechanism having a pull by which the actuating-spring is wound and then released, thereby to cause the operation of the signaling-mechanism to send its signal.

The present invention has to do particularly with a box having a normally unwound signaling-mechanism.

The invention has for one of its objects the provision of improved means adapted for operation by a local-alarm mechanism with which the box is equipped, and which is usually arranged on the door of the box, by which to operate the pull to wind the actuating-spring of the signaling-mechanism, and then to release it to cause the signaling-mechanism to send its signal. The invention also has for its object the association or combination with said improved actuating-means for the box-pull, of an improved form of local-alarm mechanism having many advantages, which is arranged to operate said actuating-means. The particular form of local-alarm mechanism, here shown for illustration, is shown and described in my application for Letters Patent No. 22,288, filed Apr. 19, 1915, being therein arranged to cause the operation of a normally wound signaling-mechanism, although the invention embodied in said application is not limited to its use in connection with such type of signaling mechanism.

Figure 1 is a front elevation of a keyless fire-alarm box, with its door open to show in elevation the local-alarm mechanism and means operated by it to actuate the normally unwound signaling-mechanism.

Fig. 2 is an enlarged elevation of the lo-

cal-alarm mechanism and actuating-member for the box.

Fig. 3 is a bottom plan view of the local-alarm mechanism and actuating-member for the box.

Fig. 4 is a transverse vertical section.

Figs. 5 and 6 are sectional views to be referred to.

The box-case 1, contains a normally-unwound signaling-mechanism of any well-known or suitable construction, which is arranged in the case and has a pull 4 projecting through a hole in the inner door 2, adapted to be pulled downward to wind the actuating-spring of signaling-mechanism and release the same, to cause said mechanism to send its signal.

The local-alarm mechanism and the actuator for said pull 4, are here shown as mounted on the inside of the outer door 5, and adapted for operation by a handle 6 or equivalent form of actuator on the outside of the outer door. The handle 6 is fixed to a shaft 7, journaled in the front and back plates 8 and 9, respectively, these plates constituting the supporting frame-work, and being rigidly held in spaced-apart relation by posts or pins 10. The shaft 7 has fixed thereon a drum 11, having a flange 12 provided with a series of recesses 13, here shown as four in number, forming ratchet-shoulders, said recesses being equally spaced around its circumference for the engagement therewith of a pawl 24, pivoted to the frame at 25, and adapted to prevent backward, and permit forward rotation of said drum. Within the drum 11 is arranged a strong coiled spring 23, having its outer end fixed to the drum, and its inner end fixed to a hub 14, which is loosely supported on the shaft 7. This spring serves as the actuating-spring for the local alarm mechanism; and said drum 11, its shaft 7, and handle 6, serve as the winding-device for said spring. The spring is wound by a turning movement of the handle in a clockwise direction and a winding operation is completed when the pawl 24 falls back of one of the shoulders.

The hub 14, which is mounted loosely on the shaft 7, has a radial web 15, which car-

100

ries at its periphery a spur gear-rim 16, here shown as laterally offset toward the drum 11, but it may be otherwise constructed. The teeth 17 of said spur-gear 5 engage and drive a pinion 37, journaled in the frame-work, the shaft of which bears an escape-wheel 38, with which co-operates a pallet 39, to which is attached an arm 40, of a bell-hammer, which is adapted to strike 10 a gong 41 as the pallet is vibrated. Said spring 23, and hub to which its inner end is connected, and spur-gear, pinion, escape-wheel, pallet, bell-hammer and gong constitute the local-alarm mechanism, which 15 is here shown for the purpose of illustrating one embodiment of my invention; and it will be noted that as the winding-device, before described, is connected with the outer end of the spring 23, said spring may be 20 wound for the purpose of accumulating power, which will be subsequently expended from the inner end of the spring for operating the local-alarm mechanism.

The inside of the spur-gear rim 16 or 25 equivalent member, which is associated with the local-alarm mechanism, is formed with notches or recesses 18, two being here shown, which are oppositely disposed, said recesses having at one side substantially radial walls 30 19, and at the other side inclined walls 20. The recesses 18 are of a depth sufficient to receive a detent 21, extending laterally from a detent-carrying arm 22, which is pivoted at 26 to the frame-work, and said detent 35 normally occupies a position in one of said recesses, thereby to hold the local-alarm mechanism at rest, and is movable out of the recess which it occupies, to release and 40 permit operation of said local-alarm mechanism.

Said detent is also arranged to prevent forward movement of the winding-device when the actuating-spring has been wound a predetermined amount, and while the local-alarm mechanism is operating. For the 45 accomplishment of this result a disk-member 29 is loosely mounted on the hub 14, next the web 15, and has opposite notches or recesses 30, which have at one side radial walls 31, and, at the other side, inclined walls 32, said recesses corresponding to the walls of said recesses 18. The recesses 30, like the recesses 18, are of a depth sufficient to receive the aforesaid detent 21. 50 Said disk-member is here shown as arranged in the same plane as the recessed gear-rim, and is of a diameter to fit loosely within said rim, so that the detent 21 may pass out of a recess in one and into a recess in 55 the other as they are moved relatively to each other, thereby engaging the rim when in one position, and the disk-member when in the other position. The disk-member 29 is arranged for operation by the winding- 60

device, being associated therewith, and, as here shown, it has a short arcuate slot 33, arranged concentrically at one side of its center which receives a pin 34 extended from the drum 11, and as the drum is turned, with the exception of the lost motion due to the length of said slot 33, said disk-member will be correspondingly turned. The turning movement of said disk-member relative to the gear by the winding-device is limited by the long arcuate slot 70 35, arranged concentrically at the other side of its center, which receives a pin 36 extended inward from the web 15, of the gear, and said slot also limits the relative turning movement of the gear 16, independently of the disk-member by its actuating-spring.

It will be noted that the detent-carrying-arm 22, bearing the detent, serves as the controlling-means or member of the local-alarm mechanism, and also of the winding-device whereby the winding-device and local-alarm mechanism are alternately held 85 from forward motion while the other is free for operation.

The gear-rim 16 is engaged by a pinion 50 secured to a shaft 51, journaled in the front and back-plates, and a snail-cam 52 which is also secured to said shaft 51, is arranged for engagement with a pin 53, 95 with or without a roll thereon, which projects laterally from one arm 54 of a bell-crank lever, the other arm 55 of which lever is made quite long, and is arranged for a swinging movement in the path of the pull 100 4. Said bell-crank lever is pivoted at 56, and is held in engagement with the edge of the cam by a spring 57. The gear 16 is designed to make a half-revolution at each operation, and the pinion to make a complete revolution, hence said members are constructed accordingly.

It will be understood that in operation, as the shaft 7 is turned in a clockwise direction by the handle 6, the spring 23 will 110 be wound from its outer end by the turning of the drum 11, while its inner end is held from escapement by the stationarily held hub 14. The hub 14 and the gear-rim 115 16 rigid therewith, are held stationarily at this time by the engagement of the detent 21, with the inclined wall 20 of one of the notches 18 on said gear-rim, the extremity of said detent being here shown as correspondingly inclined on the side that co-operates with said wall 20. The detent 21 is held from the tendency, which the inclined wall 20 under the action of spring 23 would normally have to move it out of holding position, by the periphery of the 125 disk-member 29, which engages under detent 21 and holds it up into the notch 18, an adjacent recess 30 in said disk-member.

being just past said detent in the normal position of the parts, to which position the disk-member was carried by the last operation of the gear when its pin 36 engaged 5 the end of the long slot 35, thus said disk-member serves as a holding-member for holding the detent in its normal position in engagement with the gear-rim, thereby to hold the local-alarm mechanism at rest. As 10 the manual winding or turning movement of the winding-device commences, the pin 34 on drum 11 first moves lengthwise of the short slot 33, and on arriving at the end of said slot picks up the disk-member 15 29, which latter then turns with it through the main part of the winding movement. In this winding movement the then stationary pin 36 is traversed through the long slot 35 of the disk-member 29. As soon as 20 the shaft 7 has been turned a predetermined distance to wind the spring a predetermined amount, shown in the present embodiment as a half-revolution, and just as the pawl 24 drops in behind the second 25 of the ratchet-shoulders 13, the turning movement of the disk-member 29 brings a recess 30 thereof, opposite or beneath the detent 21, which latter is then caused to move from the recess 20 into the recess 30 30 by the cam action of the inclined wall 20 of the recess 18 of the gear which at such time is permitted to move by the pressure of its actuating-spring 23, as said gear is not now restrained.

35 The local-alarm mechanism is thus released and permitted to operate by the unwinding of spring 23, until the gear-rim 16 has turned approximately a half-revolution, during which time the bell-crank lever has 40 been moved, and its arm 55 swung to depress the pull 4, thereby winding the signaling-mechanism and thereafter said bell-crank lever is released by the cam to allow the signaling-mechanism to operate to transmit the signal and the bell-crank lever is returned to its normal position by spring 57. The detent 21, during the winding, is held 45 in the notch 30 of disk-member 29. Just before the approaching notch 18 of the then 50 rotating gear-rim 16, comes opposite the detent 21, the pin 36 arrives at the end of the slot 35, and picks up the disk-member 29, turning it so that the inclined wall 32 of notch 30 in which the detent has been resting, forces said detent out of said notch 30 and into the notch 18, just as said notch 18 comes opposite said notch 30; and it will be noted that the end-portion of detent 21, engaged by the wall 32 in this operation is 55 inclined to facilitate this action. The pin 36 is so disposed relative to the notches 18 and 30, that the detent 21 is pressed up fully into the notch 18, and comes to rest against its inclined wall 20, just after the inclined

wall 32 has pressed the detent entirely out of notch 30, so that it rests flat upon the adjacent periphery of disk-member 29, as seen at Fig. 2; the slot 33 being of sufficient extent to permit the requisite movement of pin 34 in order that this movement may take place. Thus the cycle of operation is completed and the parts are ready for another winding of the spring by turning the shaft 7. It will be particularly noted that the arrangement of parts, as described, is such 75 that the local-alarm cannot be caused to sound until the handle has been turned far enough to wind and release said mechanism, and that the pull of the signaling-mechanism will be depressed during the time the 80 local-alarm is sounding, so that one does not operate except the other also does. Further, after the stem 7 has been turned to wind the spring enough so that the detent 21 is displaced and the gear-rim 16 is released to 85 start the local-alarm mechanism, both the operation of the local-alarm mechanism and the depression of the pull of the signaling-mechanism are entirely automatic and wholly out of control of the operator; so 90 that both the local-alarm will be sounded and the signaling-mechanism will necessarily be wound and released by each operation of the local-alarm device, and thereafter the parts will be automatically reset 95 for another operation without possibility of meddling or interference by an ignorant or mischievous operator.

I claim:

1. A signal-box having a normally unwound signaling-mechanism with a pull for operating it, a local-alarm mechanism having an actuating-spring, means for winding said spring, a controlling-member arranged to hold the local-alarm mechanism while its spring is being wound, and to release it and move into position to hold the winding-means while the local-alarm mechanism is operating, a pivoted arm arranged for engagement with said pull to wind the signaling-mechanism, and means operated by said spring for moving said arm in one direction to operate the pull and to release said arm, permitting independent return movement thereof to normal, said operating means being restored by the actuating-spring.

2. A signal-box having a normally unwound signaling-mechanism with a pull for operating it, a local-alarm mechanism having an actuating-spring, means for winding said spring, a controlling-member arranged to release said actuating-spring, movement of which is controlled by the winding-means at the end of the winding operation, a pivoted arm arranged for movement in the path of the pull, to engage and operate said pull, a rotatable cam driven by said actuating-spring for moving said arm in one direction

to operate the pull, which permits independent return movement of said arm to normal, said cam being restored by said actuating-spring.

- 5 3. In a signal-box, the combination of a normally unwound signaling-mechanism having a pull, a local-alarm mechanism adapted to be wound, means for winding said local-alarm mechanism, a pivoted bell-crank lever, one arm of which is arranged to move in the path of the pull to engage and operate said pull, a cam driven by the local-alarm mechanism to engage the other arm of said lever to move it to operate and 10 then release the pull, and then resume its normal position.

4. In a signal-box, the combination of a normally unwound signaling-mechanism having a pull, a local-alarm mechanism adapted to be wound, means for winding said local-alarm mechanism, a pivoted bell-crank lever, one arm of which is arranged to move in the path of the pull to engage and operate said pull, a cam rotated by the 20 local-alarm mechanism a complete cycle, adapted to engage the other arm of said lever and move it to operate the pull during the first part of its cycle of motion, and to resume its normal position during the 25 last part of its cycle of motion.

5. In a signal-box, the combination of a normally unwound signaling-mechanism having a pull, a local-alarm mechanism adapted to be wound, means for winding said local-alarm mechanism, a controlling-member arranged to hold said local-alarm mechanism while it is being wound and to release said mechanism at the end of the winding operation, and to hold the winding-means while the local-alarm mechanism is operating, a winding arm adapted for engagement with the pull to wind the signaling-mechanism, and means operated by the local-alarm mechanism adapted to move 40 said arm and release it at the end of its winding operation.

6. A signal-box having a normally unwound signaling-mechanism with a pull for operating it, a local-alarm mechanism having an actuating-spring, means for winding said spring, a controlling-member arranged to release said actuating-spring, movement of which is controlled by the winding-means at the end of the winding 50 operation, a pivoted spring-controlled bell-crank lever, one arm of which is arranged to swing in the path of movement of the pull, to engage and operate said pull, and a rotatable snail-cam driven by said actuating-spring for engaging the other arm of 55 said lever for moving said lever in one direction to operate the pull, and which permits return movement of said lever to normal.

7. A signal-box having a normally un-wound signal-mechanism with a pull for operating it, a local-alarm mechanism equipped with a spring-motor, winding-means for said spring-motor, controlling-means for said local-alarm mechanism arranged to hold it at rest while the winding-means is being operated to wind the spring, which is adapted to be moved by the winding-means at the end of its winding-motion to release the local alarm-mechanism and to lock the winding-means and hold it throughout the operation of the local-alarm mechanism, and means operated by said alarm-mechanism for operating the pull to wind the signaling-mechanism. 75

8. A signal-box having a normally un-wound signaling-mechanism with a pull for operating it, a local-alarm mechanism, means associated with said local alarm-mechanism for operating said pull to wind 80 the signaling-mechanism, said local alarm-mechanism having an actuating-spring connected at one end to operate the local alarm-mechanism, and also to operate the pull to wind the signaling-mechanism, and means 85 for winding said spring from the other end thereof, and controlling-means for holding the local alarm-mechanism from operation having provision adapted to be released by the winding-means after a predetermined 90 winding-motion thereof and then to lock the winding-means and hold it during the operation of the local-alarm mechanism.

9. A signal-box having a normally un-wound signal-mechanism with a pull for winding it, a local-alarm mechanism having an actuating-spring, a gear arranged to be driven by said spring, a detent for holding said gear while the spring is being wound, 100 winding-means for the spring arranged to control the movement of said detent at the end of the winding operation, a pinion engaging said gear, a cam arranged on the pinion-shaft, and a spring-controlled pivoted arm arranged for movement in one direction by said cam, which permits its return movement, said arm being movable in the path of the pull to engage and operate it, to thereby operate the signaling-mechanism. 110

10. A signal-box having a local-alarm mechanism associated with it, a main-spring for the alarm-mechanism, one end of which is connected with the alarm-mechanism, and 115 the other end is adapted to be wound, a winding-device for progressively winding its other end, a dog for holding its other end and the winding-device from reverse motion, a detent for preventing forward 120 motion of the opposite end of the spring until said spring has been wound a determined distance to cause a complete opera- 125

tion to be performed, means controlled by the winding-device for releasing the driving end of the spring to operate the local-alarm mechanism when the spring has been 5 thus sufficiently wound, and a winding and releasing-device for the signaling mechanism operated by the local-alarm mechanism.

In testimony whereof, I have signed my name to this specification, in the presence of two subscribing witnesses.
